UNITED STATES PATENT OFFICE.

MARK A. SHELDON, OF DETROIT, MICHIGAN, ASSIGNOR OF ONE-THIRD TO
ALEXANDER McVITTIE, OF DETROIT, MICHIGAN.

MATCH-MACHINE.

SPECIFICATION forming part of Letters Patent No. 718,393, dated January 13, 1903.

Application filed May 6, 1901. Serial No. 58,989. (No model.)

To all whom it may concern:

Be it known that I, MARK A. SHELDON, a citizen of the United States of America, residing at Detroit, in the county of Wayne and State of Michigan, have invented certain new and useful Improvements in Match-Machines, of which the following is a specification, reference being had therein to the accompanying drawings.

This invention relates to that class of continuous match-machines in which the match-splints are supplied to a splint-feeding device which sticks the splints into an endless carrier traveling in front of the feeding device and which carrier is adapted to receive and hold the splints while being converted into the finished matches; and my invention particularly relates to certain improvements in the construction of the splint-feeding device and in a carrier adapted to operate in connection therewith, all as more fully hereinafter described, and shown in the accompanying drawings, in which—

Figure 1 is a side elevation of the device for feeding the match-splints to the carrier, together with a portion of the carrier. Fig. 2 is a central longitudinal vertical section of Fig. 1. Fig. 3 is a plan of Fig. 1. Fig. 4 is a cross-section on line *x x*, Fig. 1. Fig. 5 is a cross-section on line *y y*, Fig. 2. Fig. 6 is a plan, partly in horizontal section, on line *v v* in Fig. 2. Fig. 7 is a perspective view of the hopper detached. Fig. 8 is a cross-section on line *w w*, Fig. 3. Fig. 9 is a part of the section shown in Fig. 2, illustrating the operation of the parts. Fig. 10 is an elevation of a portion of the carrier, partly in section. Fig. 11 is a longitudinal section of the carrier on a larger scale and illustrating the operation of the splint-feeding mechanism.

In the drawings, 1 represents a horizontal bed-frame upon which is secured near the discharge end of the machine horizontal feed-table 2, free to vibrate laterally, said table being secured upon the frame by screw-bolts 3, passing through slots 4 in the table, as clearly shown in Fig. 6. Upon this feed-table is secured between longitudinal guides 5 the reciprocating sticking-plate 6, formed at its discharge end with a series of longitudinally-projecting splint-guides 7, forming inter-

stices between them to receive individual match-splints. These splint-guides are rounded on top, and the end of the sticking-plate forms shoulders 8 between the guides for the ends of the match-splints.

A feed-box 9 is supported above the sticking-plate free to vibrate laterally between two fixed standards 10 of the frame, springs 11 being interposed between the sides of the box and the standards to hold the box normally in position. The feed-box is divided by longitudinal vertical partitions 12 into compartments, each adapted to hold a quantity of splints in the longitudinal direction of the machine. The bottoms of the compartments are formed by the reciprocating sticking-plate, and the sides of the compartments are formed by the feed-box except the side toward the discharge end of the machine, which is formed by a separate plate 13, removably held in position on the feed-box by the standards 14 of the frame. This separate plate rests upon shoulders 15, formed on the standards 14, and is held down by a spring 16, all as clearly shown in Fig. 8.

Above the feed-box is mounted an inclined and longitudinally-vibrating slideway 17. The lower or discharge end of this slideway is supported upon the standards 10 of the frame by means of flanges 18 on the sides of the slideway, and the upper end rests upon a frame-support 20, being secured thereto by a bolt 21, passing through a longitudinal slot 22 in the support, whereby the hopper is free to vibrate longitudinally. The upper end of the slideway is provided with any desired means for supplying it with splints, the drawings showing the upper end merely enlarged to form a hopper-like receptacle 18, adapted to hold splints in bulk.

The slideway is divided by partitions 23 into separate ways corresponding with the splint-holding compartments of the feed-box and leading into the same by having the bottom of said ways terminate at the junction with the feed-box, while the sides of the ways extend over the feed-box.

The bottom of the slideway changes near the discharge end to a level, and in this level portion is formed a transverse slot, in which is journaled a serrated feed-roller 24. The

face of this roller projects above the bottom of the discharge-way, except that the portion 25 at the extreme end beyond the roller is made, preferably, on a level with the top of 5 the roller. Above the feed-roller in each of the separate ways is mounted a pressure-foot 26, each adapted to bear upon the top of the roller. These pressure-feet are pivotally secured upon the transverse rod 27 and extend 10 with their free ends, which are free to rise and fall, over the roller and the portion of the ways beyond it, and each has a shoulder 28 formed on its under side in advance of the roller.

15 Motion is communicated to the parts by means of a drive-shaft 45, journaled laterally of the frame and carrying a pinion 46, which imparts motion to a shaft 29 through a gear-wheel 47, and the shaft 29 imparts motion to 20 another shaft 30, which is journaled longitudinally of the frame upon brackets 31 through the intermediate bevel-gears 32. The shaft 29 carries a ratchet-wheel 33, and an arm 34, secured to the under side of the 25 slideway and carrying a striker-plate 35, which is held to bear against the face of the ratchet-wheel by a spring 36, imparts to the slideway a quick to-and-fro motion. The shaft 30 carries a ratchet-wheel 37, and 30 the feed-box has secured to it a striker-plate 38, which projects into the path of the teeth of said ratchet-wheel, whereby the motion of the shaft 30 imparts a continuous lateral vibration to the feed-box. The shaft 30 also 35 has secured upon it two segmental ratchet-wheels 39, having only a few ratchet-teeth, and to the adjacent ends of the feed-table are secured two striker-arms 40, projecting into the path of the ratchet-teeth and coöperating with 40 two springs 41, (see Fig. 5,) secured beneath the feed-table and operating by their tension to hold the striker-arms in the path of the ratchet-teeth, all so arranged that at certain fixed intervals in the revolution of the shaft 45 30 a lateral vibrating motion is imparted to the feed-table, in which motion the sticking-plate partakes as it is embedded in the feed-table.

The sticking-plate 6 is reciprocatingly actuated by means of a connecting-rod 42, fastened to a crank-pin 43 on the ratchet-wheel 33, and motion is imparted to the feed-roller 24 by means of a sprocket-and-chain connection with the drive-shaft.

55 The parts being constructed and arranged as described and shown are intended to operate as follows: If splints are thrown into the upper end of the slideway or supplied in bulk into the hopper, the constant to-and-fro motion will cause them to feed down the slide-way or slideways, and as these are made sufficiently narrow the splints are straightened out. At the lower end of the slideway the pressure-foot, aided by its shoulder 28 and by 60 the bevel portion of the bottom, prevents the free discharge of the splints, and only the bottom splints are pulled along by making

contact with the sharpened face of the feed-roller owing to the pressure-foot holding them down upon it. Splints thus carried forward 70 by the motion of the roller pass beneath the pressure-foot and are thus held down and prevented from falling till each splint reaches the very bottom. At the instant each splint is released it is thus in a perfectly horizontal position and entirely free to drop into the feed-box (the interior length of which is greater than the length of the splint) without one end falling in advance of the other, and the result is that the splints will pile up in the different compartments of the feed-box in perfect horizontal layers, and it will make no difference if there are any short or broken splints. In the use of square match-splints 85 it will also be seen that as each splint is carried over the feed-roll with one of its flat sides down it will fall into the feed-box the same way, and thus the splints pile up in layers, aided by the vibrating motion of the feed-box. The feed-roller having a concerted 90 movement with the other moving parts of the machine revolves fast enough to keep up the supply of splints in the feed-box; but if from one cause or another the supply of splints in the feed-box should become low it 95 will make no disturbance. From the feed-box the splints are fed to the reciprocating sticking-plate, which in its most rearward position has its slotted portion directly below the feed-box, while at the same instant segmental ratchets 39 strike the arms 40 of the feed-table, and thereby impart to the sticking-plate a jarring lateral motion, which causes individual splints to enter into the interstices between the splint-guides. By the 100 forward motion of the sticking-plate these splints will be carried along with the plate as the shoulders 8 impinge against the end of the splints, while the guides hold the splints between them. Thus confined they are carried out of the box beneath the plate 13 to the discharge end of the machine far enough to have the projecting ends of the splints enter the splint-holding devices of a suitable carrier adapted to receive rows of splints and 105 traveling in vertical guides at the end of the feed-table with a step-by-step motion in the usual manner.

Most of the known constructions of endless carriers having perforations, interstices, or 110 other equivalent means for sticking rows of splints into them may be used in connection with my feeding device; but the construction of carrier shown in the drawings may be used with particular advantage for making the 115 kind of matches which require dipping the splint at both ends, one end receiving the igniting composition and the other end being dipped into a solution, making the splint non-combustible. This carrier, a short section of 120 which is shown in the drawings, is composed of a series of like frames hinged together, each frame secured midway of its length on 125 opposite sides to ordinary sprocket-chains 130

for imparting motion to the carrier in the well-known manner. Each frame is composed of two side bars 51 and a series of cross-bars 52, rigidly secured to the side bars at equal 5 distances apart. Each cross-bar is formed alike, with a series of grooves 53 in one side and with a series of spring-fingers 54 secured to the other side. These fingers are preferably cut of a single plate of sheet metal, united 10 at the base, like the teeth of a comb, by a continuous portion 55, which is secured to the cross-bar, while the fingers are bent back U shape upon the base and extend opposite the grooves of the adjacent bar, forming there- 15 with spring-jaws for holding match-splints.

While splint-carriers composed of plates hinged together and provided with splint-receiving devices of the character described are not new, I have adopted this type of carrier 20 to produce a new result in connection with my splint-feeding device. To this end I make the spaces between the fingers large enough to form passages for the splint-guides, and instead of sticking merely the ends of the 25 splints into the spring-jaws I shove the splints through the carrier, so that they project at both ends, and in doing so the splint-guides pass through the intervals between the fingers and hold and guide the splints while being stuck into the carrier. I also preferably curve the spring-fingers in the manner shown to clamp the splint at two separate points, so that it will be held more firmly in the carrier.

As my improvements are directly applicable to other match-machines of like character in present use and will be fully understood without reference to any other parts required to make a complete working match-machine, I have omitted to show or describe 40 any parts which have no bearing on my invention.

What I claim as my invention is—

1. In a splint-feeding mechanism, the combination with a splint-feeding slideway and 45 a box or receptacle below the end of the slideway to receive the falling splints, of a pressure-foot in the end of the slideway beneath which the splints have to pass, said pressure-foot coöoperating with the slideway to hold 50 each splint from falling before reaching the end of the slideway.

2. In a splint-feeding mechanism, the combination with a splint-feeding slideway and a box or receptacle at the end of the slide- 55 way and adapted to receive the falling splints from said slideway, of a pressure-plate above and coextensive with the end portion of the bottom of the slideway and adapted to coöperate therewith to hold the splints from fall- 60 ing before reaching the end of the slideway and a feed-roller below said pressure-plate and coöoperating therewith to feed the splints beneath said plate.

3. In a splint-feeding mechanism, the com- 65 bination with a slideway communicating at one end with a source of splint-supply, and at its other end with a compartment or box

placed beneath the end and adapted to receive the falling splints from said slideway, of means for feeding the splints through said 70 slideway, and a pressure-foot in the discharge end of the slideway above the bottom thereof and adapted to bear upon the ends of the splints in passing beneath said pressure-foot.

4. In a splint-feeding mechanism, the com- 75 bination with a slideway arranged and adapted to conduct splints from a source of supply and discharge them into a compartment or box below its discharge end, of a pressure- foot at the discharge end of the slideway 80 adapted to bear upon the ends of the splints and hold them from falling before leaving the end of the slideway.

5. In a splint-feeding mechanism, the com- 85 bination with a slideway arranged and adapted to conduct splints from a source of supply into a box or compartments below the dis- charge end of the slideway, of a pressure-foot pivotally secured in the discharge end of the 90 slideway free to rise and fall therein and operating by its weight to prevent the splints from falling before clearing the end of the slideway.

6. In a splint-feeding mechanism, the com- 95 bination of a splint-feeding slideway having its bottom inclined from the upper end to near the lower end, and provided with a level portion at the lower end, a pressure-foot mounted in said slideway above said level portion and adapted to bear upon the splints in 100 leaving the slideway and means for controlling the passage of splints beneath said pressure-foot.

7. In a splint-feeding mechanism, the com- 105 bination of a splint-feeding slideway having its bottom inclined from the upper end to near the lower end and provided with a level portion at the end of the slideway, a pressure- foot hinged above the slideway free to rise and fall and having a bearing-plate extending 110 over the level portion at the end of the slideway and adapted to bear upon the ends of the splints as they leave the end and means for controlling the passage of the splints beneath said pressure-foot. 115

8. In a splint-feeding mechanism, the com- 120 bination of an inclined slideway, a source of splint-supply at the upper end thereof, means for agitating the slide to feed the splints to the lower end of the slideway, a transverse slot in said lower end, a feed-roller journaled in said slot and a pressure-foot adapted to bear upon the roller and extending over the end of the slideway beyond the roller and co- 125 operating therewith to prevent the splints from falling after passing the roller.

9. In a splint-feeding mechanism, the com- 130 bination of a slideway communicating at its upper end with a source of splint-supply, and having an inclined bottom terminating at its lower end in a substantially level portion, a transverse slot in said level portion, a feed-roller journaled in said slot, means for agitating the slideway, and a pressure-foot having

a bearing-face extending over the roller and the end of the bottom of the slideway beyond the roller.

10. In a splint-feeding mechanism, the combination of a splint-feeding slideway having an inclined bottom terminating at its lower end in a substantially level portion, an opening in said level portion, a feed-roller transversely journaled in said opening and projecting with its periphery above said opening, and a pressure-foot adapted to bear upon the splints in passing over the feed-roller, the bearing-face of said pressure-foot being substantially on a level and extending beyond the feed-roller to the end of the bottom of the slideway.

11. In a splint-feeding mechanism, the combination of a splint-feeding slideway having an inclined bottom terminating at its lower end in a substantially level portion, an opening in said level portion, a transverse feed-roller projecting through said opening, and a pressure-foot above the feed-roller and adapted to coöperate therewith to feed the splints over the roller, said pressure-foot having a shoulder in advance of the feed-roller for the purpose of insuring a uniform passage of splints over the roller.

12. In a splint-feeding mechanism, the combination of a splint-feeding slideway having an inclined bottom, level near its lower end, a transverse feed-roller in an opening near said lower end and projecting with its periphery through said opening, into the slideway, and a pressure-foot having a bearing-plate extending over the roller and over the portion of the bottom of the slideway beyond the roller, said portion being substantially on a level with the top of the roller.

13. In a splint-feeding mechanism, the combination of an inclined splint-feeding slideway having a hopper at the upper end thereof, adapted to receive splints in bulk and feed the same unto the slideway, a box at the lower end of the slideway and adapted to receive the splints as they fall from the slideway, a pressure-plate pivotally secured free to rise and fall in the slideway and adapted to bear upon the splints in leaving the end of the slideway, a shoulder on said pressure-plate adapted to bar the passage of more than one layer of splints beneath said plate, and a feed-roller transversely journaled in an opening in the bottom of the slideway beneath the pressure-plate and adapted to coöperate therewith to feed the splints beneath the pressure-foot.

14. In a splint-feeding mechanism, the combination of an inclined slideway adapted to feed splints from a source of supply into a box or receptacle, a pressure-plate pivotally secured in the slideway free to rise and fall and adapted to bear upon the splints in leaving the end of the slideway, and a feed-roller in an opening in the bottom of the slideway below the pressure-plate and adapted to coöperate with the pressure-bar to feed the

splints beneath the pressure-plate, said pressure-plate projecting in advance of the roller and having a shoulder operating to bar the passage of more than one layer of splints between the pressure-bar and the top of the feed-roller.

15. In a splint-feeding mechanism, the combination of a slideway having its bottom formed with an incline, and with a level portion at the foot of the incline, means for supplying splints into the slideway at the top of the incline, a box or receptacle beyond and below the level portion of the slideway to receive the falling splints, means for agitating the slideway to feed the splints from the source of supply to the foot of the inclined portion of the slideway, a transverse feed-roller mounted in an opening in the level portion of the slideway and projecting into the same, and a pressure-plate secured above the roller free to rise and fall and adapted to coöperate with the roller and with the end of the slideway beyond the roller to feed the splints beneath said pressure-plate and keep them from falling till they reach the end of the slideway, said pressure-plate projecting in advance of the roller and forming a shoulder adapted to bar the entrance of more than one layer of splints beneath it.

16. In a splint-feeding mechanism, the combination of the inclined slideway 17, having means for agitating the same, the feed-hopper 18 mounted upon the upper end thereof, the longitudinal partitions 23 dividing the slideway, the feed-roller 24 transversely journaled in an opening in the bottom of the slideway, and the pressure-plate 26 pivotally mounted in the slideway above the feed-roller, one in each division of the slideway, and adapted to coöperate with the roller and with the bottom of the slideway to discharge the splints from the slideway in a horizontal position, each pressure-foot extending in advance of the feed-roller and forming a shoulder operating as a stop to regulate the passage of the splints beneath the pressure-foot.

17. In a splint-feeding mechanism, the combination with a supporting bed-frame, of a splint-feeding slideway, a source for supplying the same with splints, a laterally-vibrating feed-box below the end of the slideway adapted to receive the falling splints, means in the slideway to insure a horizontal discharge of the splints from said slideway, a reciprocating sticking-plate below the feed-box formed at its forward end with longitudinal projections or splint-guides adapted to receive individual splints in the interstices between the same, a feed-table upon which said sticking-plate is supported in longitudinal guides, means for imparting periodically a vibrating motion to the feed-table and a carrier at the end of the feed-table adapted to receive the row of splints from the sticking-plate.

18. In a splint-feeding mechanism, the combination of a reciprocating sticking-plate hav-

ing slots or interstices adapted to receive individual splints and stick the same into a carrier, of a feed-box mounted above said sticking-plate free to vibrate and adapted to supply the same with splints, means for vibrating the feed-box laterally independently of the sticking-plate, a feed-table upon which said sticking-plate is supported free to reciprocate in longitudinal guides in said table and means for imparting a periodically-vibrating motion to the feed-table.

19. In a splint-feeding mechanism, the combination of a reciprocating sticking-plate having slots or interstices adapted to receive individual splints and stick the same into a carrier, a feed-table upon which said sticking-plate is supported in longitudinal guides, means for periodically vibrating said feed-table, a feed-box supported upon said table free to vibrate independently thereof and adapted to supply the sticking-plate with splints and a slideway leading into the top of the feed-box and adapted to supply the same with splints, said slide having a longitudinal to-and-fro motion independently of the feed-box.

20. In a splint-feeding mechanism, the combination with a horizontal supporting-frame, a feed-table mounted upon said frame, means for vibrating said feed-table periodically, a reciprocating sticking-plate mounted in longitudinal guides upon said feed-table and provided with slots in its forward end adapted to receive a row of individual splints, a carrier beyond the end of the feed-table adapted to receive the splints from said sticking-plate, a feed-box mounted upon the feed-table above the sticking-plate free to vibrate and adapted to supply the sticking-plate with splints, an inclined slideway leading into the top of the feed-box and adapted to supply the same with splints, a feed-hopper surmounting the upper end of said slideway and adapted to receive splints in bulk, and means applied to said slideway for feeding the matches from said hopper into the feed-box.

21. In a splint-feeding mechanism, the combination of an inclined slideway communicating at its upper end with a source of splint-supply, and adapted to discharge the splints at its lower end, a feed-box below said lower end in position to receive the falling splints, means in the end of the slideway to cause the splints to pass beyond the end of the slideway before falling, means to vibrate the feed-box laterally, a feed-table below said feed-box, means for periodically vibrating said feed-table, a reciprocating sticking-plate secured in horizontal guides in the feed-table below the feed-box, and provided with longitudinal slots adapted to receive a row of individual splints from said feed-box, and a carrier adapted to receive the splints from the sticking-plate.

22. In a splint-feeding mechanism, the combination with a splint-receiving feed-box and a reciprocating sticking-plate adapted to re-

ceive the splints from said feed-box, of a splint-feeding slideway communicating at one end with a source of splint-supply and adapted to discharge said splints at the other end free to fall into the feed-box, and means in the discharge end of the slideway for preventing the splints from falling before reaching the end of the slideway.

23. In a splint-feeding mechanism, the combination with a splint-receiving feed-box and a reciprocating sticking-plate arranged below the feed-box and adapted to receive the splints from said feed-box, of a splint-feeding slideway communicating at one end with a source of splint-supply and adapted to discharge said splints at the other end free to fall into the feed-box, and means in the slideway to bear upon the ends of the splints as they leave the slideway, to prevent them from falling before reaching the end of the slideway.

24. In a splint-feeding mechanism, the combination with a splint-receiving feed-box and a reciprocating sticking-plate arranged below the feed-box and adapted to receive the splints from said feed-box, of an inclined splint-feeding slideway communicating at its upper end with a source of splint-supply and adapted to discharge said splints at the lower end free to fall into the feed-box and means at the discharge end of the slideway adapted to bear upon the ends of the splints to prevent them from falling before leaving the end of the slideway, the end of the slideway being formed upon a level.

25. In a splint-feeding mechanism, the combination with a splint-receiving feed-box and a reciprocating sticking-plate arranged below the feed-box and adapted to receive the splints from said feed-box, of an inclined splint-feeding slideway leading with its lower end into the top of the feed-box and adapted to discharge the splints endwise free to fall into said box, said slideway and feed-box correspondingly divided by partitions into compartments, the compartments of the slideways forming separate ways for the splints, each provided in its lower end with means for preventing the splints from falling into the feed-box before leaving the end of the slideway.

26. In a splint-feeding mechanism, the combination with the frame, the feed-table supported thereon free to vibrate laterally and the carrier at the end of the feed-table adapted to receive a row of splints, of a reciprocating sticking-plate held in guides upon the feed-table and adapted to receive a row of individual splints and stick them into the carrier, means for periodically vibrating the feed-table, a feed-box mounted above the sticking-plate free to vibrate independently thereof, and adapted to supply the sticking-plate with splints and means for vibrating said feed-box, said feed-box having the wall beneath which the splints are withdrawn from said box formed by a separate plate free to rise and fall vertically independently of the feed-box

and a spring to hold said plate in normal position.

27. In a splint-feeding mechanism, the combination with the supporting-frame, the feed-table thereon, the carrier at the end of the feed-table adapted to receive rows of splints and the reciprocating splint-sticking plate upon the feed-table and adapted to receive a row of individual splints and stick the same into the carrier, of the feed-box mounted above the sticking-plate and adapted to supply the same with splints the standards 10 on the frame between which the feed-box is supported, the springs 11 interposed between said standards and the ends of the feed-box, means for vibrating the feed-box, the separate plate 13 forming the side of the feed-box on which the splints are discharged, said plate secured in position independently of the feed-box free to rise and fall and the spring 16 vertically pressing upon said plate and normally holding it in position with its lower edge in close proximity to the sticking-plate.

28. In a splint-feeding mechanism, an in-

clined splint-feeding slideway adapted to receive splints from a source of splint-supply at its upper end and discharge the same at the lower end free to fall, and a weight in the lower end of the slideway adapted to bear upon the ends of the splints in leaving the slideway to prevent them from falling before leaving the end of the slideway, said end being formed upon a horizontal plane.

29. In a splint-feeding device, the combination of an inclined splint-feeding slideway communicating at one end with a source of splint-supply, means in said slideway to insure a uniform passage of splints through the slideway to the opposite ends and a weight in the end of the slideway to bear upon the ends of the splints and prevent them from falling before leaving the end of the slideway.

In testimony whereof I affix my signature in presence of two witnesses.

MARK A. SHELDON.
